UNITED STATES PATENT OFFICE

BERTRAM PARROTT GRAY, OF BIRMINGHAM, ENGLAND

HORSESHOE

Application filed March 27, 1930, Serial No. 439,396, and in Great Britain May 29, 1929.

This invention relates to resilient pads for horseshoes, and refers more particularly to that class of device which is described in my prior Patent No. 1,320,000, granted 28th October, 1919, wherein the device comprises a wearing pad of rubber or the like with which is associated a resilient plate of metal which extends in the manner of a bridge across the heel ends of the horseshoe, the plate preferably being arranged so that it receives frog pressure.

The object of the present invention is to provide an improved construction of pad.

Referring to the drawings:

Figure 1 is a perspective view showing one form of the invention,

Figure 2 is a sectional view taken longitudinally through the wearing pad on line 2-2 of Figure 1,

Figure 3 is a transverse section on line 3-3 of Figure 1,

Figure 4 is a perspective view showing another construction,

Figure 5 is a side view showing another modification,

Figure 6 is a perspective view showing further modifications, and

Figure 7 is a sectional view showing a further modification.

In the construction shown in Figures 1, 2 and 3, the heel ends 1 of the horseshoe 2 are in this case provided with downward extensions or calks 3.

The wearing pad 4 of rubber, rope, or other material, is carried by a thin flexible metal plate 5 having longitudinal turned-under parts 5^a adapted to engage the wearing pad and secure the latter to the plate 5, and the wearing pad extends across the whole width of the heel portions of the shoe.

The ends of the metal plate 5 extend entirely or partially across the upper surface of the heel portions of the shoe, which may be reduced in thickness or recessed under the heel or load portion, while the ends of the wearing pad, which also may be reduced in thickness, extend entirely or partially under the heel portions.

In this construction the calks 3 prevent the wearing pad from moving rearwardly,

but in order to prevent forward or other movement, the ends of the metal plate 5 may be riveted or otherwise secured if necessary to the shoe 2.

For instance, the metal plate 5 may be provided with integral forward extensions or ears 6 which are riveted to the shoe, the rivets thus being out of line with the ends of the wearing pad, and not extending therethrough. In addition to the extensions 6, or instead of the extension 6, the metal plate 5 may be provided with integral or other rear extensions or ears 7 which extend down over the ends of the shoe and thus prevent forward movement even without riveting.

Instead of using either the extension 6 or the extension 7, or in addition to using either of them, one or more rivets may be used extending through the wearing pad and the shoe and the metal plate 5. Such a rivet (or rivets) is shown in Figure 7, and for forming such a rivet, a horseshoe nail or the like may be used.

If required, the wearing pad of rubber or the like may have a strengthening sheath or sheaths 8 of metal or other suitable material embedded therein for receiving the head of the nail or rivet. The sheath may be placed under the nail head before it is driven in. There may be one, two or more of such rivets at each end of the appliance.

In the construction shown in Figure 4, instead of the plate 5 extending across the top of the end portions of the shoe, the plate 5 is cranked and its end portions 9 extend under the end portions of the shoe, the middle portion of the plate 5 being cranked upwardly so as to receive frog pressure.

In Figure 4 I have shown the invention applied to a shoe in which the heel ends are not bent downwardly but are recessed, as shown at 10, for receiving the wearing pad 4.

The recess 10 may be formed substantially as shown in Figure 4, or instead of having the vertical shoulder 11, the recess may be formed with an inclined shoulder such as 12, as shown in Figure 5.

In Figure 5 also the plate 5 is shown as extending across the top of the shoe, but it might be arranged as shown in Figure 4.

In either case the end portions 9 of the plate 5, with or without the end portions of the wearing pad, may be attached to the shoe by one or more rivets such as 13, but it is preferred to use two or even more rivets at each end so that if the appliance should break in the center then the two pieces thereof will be unable to pivot upon the ends of the shoe.

The metal plate 5 is preferably weakened 10 at the center as shown at 15.

It is to be understood that the method of mounting the appliance shown in Figures 1 to 3 may be employed in connection with the shoes in Figures 4 and 5, while the method of 15 constructing and mounting the appliance shown in Figures 4 and 5 may be applied to the shoe as shown in Figure 1.

Further, the fastening means or locating means shown in Figures 6 and 7 may be employed either with the construction shown in Figure 1, or with the construction shown in Figure 4. If the bent-over portions 7 are to be used with the construction shown in Figure 4, however, they are bent upwardly instead of downwardly, and the forward extension 6, while hardly applicable to the construction shown in Figure 4, would be used with the construction shown in Figure 5.

What I claim then is:—

30 1. A resilient pad for a horseshoe comprising in combination a resilient plate adapted to be attached by its ends across the heel of a horseshoe, a wearing pad attached to said resilient plate and adapted to extend entirely across the heel of the shoe below the latter, and said wearing piece being recessed at its ends to receive the heel ends of the shoe.

40 2. A resilient pad for a horseshoe comprising in combination a plate adapted to be attached by its ends across the heel of a horseshoe, said plate being weakened between its ends to make the plate resilient, a wearing pad attached to said resilient plate and adapted to extend entirely across the heel of the shoe below the latter, and said wearing piece being recessed at its ends to receive the heel ends of the shoe.

45 3. A resilient pad for a horseshoe comprising in combination a plate adapted to be attached by its ends across the heel of a horseshoe, said plate being weakened between its ends to make the plate resilient, a wearing pad attached to said resilient plate and adapted to extend entirely across the heel of the shoe below the latter, said wearing piece being recessed at its ends to receive the heel ends of the shoe, and means for preventing the movement of the said plate relative to the shoe.

55 4. A resilient pad for a horseshoe comprising in combination a plate adapted to be attached by its ends across the heel of a horseshoe, said plate being weakened between its ends to make the plate resilient, a wearing pad attached to said resilient plate and

adapted to extend entirely across the heel of the shoe below the latter, said wearing piece being recessed at its ends to receive the heel ends of the shoe, and means for preventing the movement of the said plate relative to the shoe comprising rivets passing through the plate and the shoe.

5. A resilient pad for a horseshoe comprising in combination a plate adapted to be attached by its ends across the heel of a horseshoe, said plate being weakened between its ends to make the plate resilient, a wearing pad attached to said resilient plate and adapted to extend entirely across the heel of the shoe below the latter, lugs or ears on the ends of said plate, and rivets adapted to pass through said ears and the heels of the shoe.

6. A resilient pad for a horseshoe comprising in combination a plate adapted to be attached by its ends across the heel of a horseshoe, said plate being weakened between its ends to make the plate resilient, a wearing pad attached to said resilient plate and adapted to extend entirely across the heel of the shoe below the latter, said wearing piece being recessed at its ends to receive the heel ends of the shoe, said plate having longitudinal turned-under parts adapted to engage said wearing pad, the ends of said plate being disposed above the heel of the shoe and the ends of said pad below such heel.

7. A resilient pad for a horseshoe comprising in combination a plate adapted to be attached by its ends across the heel of a horseshoe, said plate being weakened between its ends to make the plate resilient, a wearing pad attached to said resilient plate and adapted to extend entirely across the heel of the shoe below the latter, said wearing piece being recessed at its ends to receive the heel ends of the shoe, said plate having longitudinal turned-under parts adapted to engage said wearing pad, the ends of said plate being disposed above the heel of the shoe and the ends of said pad below such heel, and means for preventing the movement of the said plate relative to the shoe comprising rivets passing through the plate and the shoe.

8. A resilient pad for a horseshoe comprising in combination a plate adapted to be attached by its ends across the heel of a horseshoe, said plate being weakened between its ends to make the plate resilient, a wearing pad attached to said resilient plate and adapted to extend entirely across the heel of the shoe below the latter, said wearing piece being recessed at its ends to receive the heel ends of the shoe, said plate having longitudinal turned-under parts adapted to engage said wearing pad, the ends of said plate being disposed above the heel of the shoe and the ends of said pad below such heel, lugs or ears on the ends of said plate, rivets adapted to pass through said ears and the heels of the shoe.

shoe, and downwardly projecting ears on said plate adapted to engage the extreme rear ends of the shoe.

9. In combination, a horseshoe having downwardly projecting heel pieces, a wearing pad extending entirely across the heel part of the shoe in advance of and abutting against said heel pieces, and a resilient plate attached to the upper surface of said pad and extending transversely between the heel ends of said shoe.

10. In combination, a horseshoe having downwardly projecting heel pieces, a wearing pad extending entirely across the heel part of the shoe in advance of and abutting against said heel pieces and recessed at its ends to receive the rear parts of the shoe, a resilient plate attached to the upper surface of said pad and extending transversely between the heel ends of said shoe, and means for securing said wearing pad on the shoe.

11. A resilient pad for a horseshoe comprising in combination a resilient plate adapted to extend between the heel ends of the horseshoe, a wearing pad attached to said resilient plate and adapted to extend across the heel ends of the shoe below the latter, the wearing pad being recessed at its ends to receive said heel ends of the shoe, and means for connecting the wearing pad to the shoe.

In witness whereof I affix my signature.

BERTRAM PARROTT GRAY.
